INSULATOR CLAMPING DEVICE

William L. Scott, Jr., Oak Ridge, Tenn., assignor, by mesne assignments, to the United States of America as represented by the United States Atomic Energy Commission

Application July 21, 1945, Serial No. 606,405

6 Claims. (Cl. 174—163)

This invention relates to a supporting device for members such as insulators or the like which are exposed to a relatively wide range of temperature. Insulators are often made of ceramic materials or other materials having like characteristics which have a different temperature coefficient of expansion than metals from which supporting devices are ordinarily made. The insulators must be firmly supported, that is clamped, or gripped at ordinary temperatures and must be similarly firmly supported, often at considerably higher temperatures. The arrangement must be such that at rising temperatures the supporting means continues to firmly support the insulating member but without producing so much stress therein as to fracture, deform, or misalign the insulator.

This is particularly important in some types of apparatus wherein insulating members constitute the supporting means for electrodes or other elements which must be maintained in very accurate alignment over a considerable range of temperature and at times also while under the influence of a strong magnetic field. An object of my invention is therefore to provide supporting means for an insulator or the like which will firmly support the insulator over a wide range of temperature without allowing the insulating member to become loose and without applying excess force such as to produce stresses which might fracture, deform or misalign the insulator.

Another object of the invention is to provide supporting means for an insulator or the like comprising a clamping arrangement formed of material having a different coefficient of expansion than material of the insulator and embodying a resiliently deformable member so arranged that upon rising temperature the resiliently deformable member compensates for the different expansion in the clamping means than in the material of the insulator.

Another object of the invention is to provide supporting means for insulators or the like comprising a clamping device so arranged that a part thereof is under spring tension when in clamping position and so that upon rising temperature, even though the clamping device expands at a different rate than the material of the insulator, the spring tension is such as to cause the insulator to be firmly clamped.

Another object of the invention is to provide supporting means for an insulator or the like comprising resiliently deformable clamping members arranged to be clamped against the insulator and placed under spring tension and so arranged that the clamping force is substantially the same over a wide range of temperature even though the material of the clamping members expands at a different rate than the material of the insulator.

Another object is to provide an arrangement as in the preceding object wherein the clamping members are arcuate and have such a radius of curvature as to normally engage the insulator at their ends.

Another object of the invention is to provide supporting means for an insulator or the like comprising deformable clamping members arranged to be clamped against the insulator, the ends of the members frictionally engaging the insulator to permit free thermal expansion circumferentially of the insulator.

Another object is to provide an insulator and clamping members as in the previous objects wherein the insulator and clamping members have mutually engaging surfaces so shaped as to prevent lateral displacement of the members along the insulator.

Further objects and numerous of the advantages of

2

my invention will become apparent from the following detailed description and annexed drawings wherein:

Fig. 1 is a view partly in cross section of an insulator supported by the improved supporting means of my invention.

Fig. 2 is a view partly in section taken along the line 2—2 of Fig. 1.

Fig. 3 is a plan view of a detail of Fig. 1 taken along line 3—3 of Fig. 1.

Referring to the drawings, numeral 10 designates an insulator or insulating member of standard type fluted construction which is supported in the improved manner of my invention. The insulator 10 extends outwardly from a metal plate 11 to which it is attached as will be described. Numeral 12 designates a shield which is around the insulator and which is attached to the plate 11 by soldering as shown. The shield 12 forms a protective device for the insulator to protect it from bombarding particles and it has a continuous bead 13 attached to its outer edge, the purpose being to eliminate sharp edges which are conducive to electrical arcing.

Numeral 16 designates a plurality of lugs, of which there are three, which are soldered to the plate 11 and to the shield 12 in a circle spaced at 120° intervals as may be seen on Fig. 2. The lugs 16 are rectilinear in shape and to each of them is attached a clamping element 17 which clamps the insulator 10. The left end of the insulator 10 is circular but its conformation is such as to form two oppositely tapering surfaces as shown in cross-section on Fig. 1. Each of the clamping elements 17 has a groove at its upper part as shown on Fig. 1 in which engages a shoulder or rib on the lugs 16, the mutually engaging parts of the elements 17 and the lugs 16 being convex and concave respectively. Numeral 20 designates set screws which extend inwardly through the lugs 16 and which are adjustable through openings in the shield 12, the set screws bearing against the elements 17 whereby the said elements can be adjusted or forced inwardly, that is, radially against the insulator 10. The elements 17 are concave on their inner sides and they have oppositely tapering surfaces as shown on Fig. 1 which match the tapering surfaces on the insulator 10 and mutually engage therewith. However, the radius of curvature of elements 17 is slightly smaller than the radius of curvature at the left end of the insulator 10 so that the contour of the elements 17 does not conform exactly to the surface of the insulator 10 as may be seen at Fig. 2. Each of the elements 17 has a central depression on its concave side as may be seen on Fig. 1, the elements 17 being somewhat greater in extent circumferentially of the insulator than the lugs 16 as may be seen on Fig. 2.

From the foregoing it will be observed that by tightening up on the set screws 20 the elements 17 are caused to bear tightly against the tapering surfaces of the insulator 10 thus placing the elements 17 under spring tension, these elements being resiliently deformable. The force exerted by the elements 17 to clamp or grip the insulator 10 of course depends upon the amount of spring tension on the elements 17 as developed by tightening up on the set screws 20. Elements 17 are constructed, for instance, of spring steel or other suitable material having a resilient characteristic, and are designed, as to dimensions, such that they may be deformed through the necessary range of operation without breaking. The oppositely tapering matching surfaces prevent movement to right or left of the insulator when it is in clamped position. Upon rising temperature in the vicinity of the insulator, the material of the clamping members that is the elements 17 and the lugs 16 and the set screws will expand faster than the material of the insulator which may be of ceramic for example. Thus due to the radial expansion of the lugs 16 and the elements 17 the tendency will ordinarily be to clamp or grip the insulator more firmly, the expansion of plate 11 not being appreciable; however, there will also be lateral expansion of the element 17 relatively to the insulator and, due to the fact that these elements are resilient and under spring tension, further deformation of them is permitted and their normal contour tends to conform more nearly to the contour

or surface of the insulator 10. The effect is that as the temperature rises the insulator 10 is clamped or gripped with substantially the same force by the clamping elements 17. To explain this effect more specifically, if the temperature rises, due to the longitudinal expansion of lug 16 and set screw 20, the distance between the insulator 10 and the point of engagement of lug 16 and clamping element 17 decreases. If the normal (undeformed) contour of clamping element 17 were to remain the same, there would thus result a greater deformation of clamping element 17 from its normal contour, and therefore a greater clamping force upon the insulator. However, as the temperature rises, there is a simultaneous straightening out of the clamping member 17 with the result that it acquires a new normal contour corresponding to the new higher temperature, this new normal contour conforming more closely to that of the adjacent surface of the insulator, and decreasing that amount of deformation of the clamping element from its normal contour which corresponds to any particular distance between the insulator and the point of engagement of lug 16 and clamping element 17. Thus, if this latter distance remained the same, the deformation of clamping element 17, and the clamping force upon the insulator, would both decrease. Thus there are two mutually opposing effects accompanying any temperature change. The resiliency of clamping element 17 is made by design just sufficient, taking into consideration the dimension and temperature coefficients of expansion of the various associated portions of the device, for these mutually opposing effects to substantially cancel each other out, whereby the insulator is always retained by the clamping elements with substantially constant force. The insulator is thus held firmly at all temperatures without misalignment and stresses are not developed such as to be so excessive as to fracture, deform or misalign the insulator itself. The spring tension in elements 17 compensates for any relative changes in dimensions of parts caused by temperature changes.

From the foregoing those skilled in the art will observe that I have provided an efficient and simple device whereby insulators and the like may be firmly supported and subjected to a wide range of temperature without loss of support and without danger of fracturing or otherwise breaking the insulator or deforming it or forcing it out of its proper original alignment.

I claim:

1. In a support for insulators and the like, in combination, means comprising at least one resiliently deformable clamping member for holding the insulator, and means associated with the clamping member for deforming it to apply a spring force against the insulator, said clamping member being arcuate and having a radius of curvature less than that of an adjacent portion of said insulator, whereby only its opposite ends normally engage the insulator.

2. In a support for insulators and the like, in combination, at least one arcuate resiliently deformable clamping member having a radius of curvature less than that of an adjacent portion of said insulator, whereby opposite ends thereof are adapted to bear against the insulator portion, and means associated with said clamping member for applying an inwardly directed radial deforming force against said clamping member, whereby said insulator is held in place by the spring force exerted by

said ends resulting from the deformation of said clamping member.

3. In a support for insulators and the like, in combination, at least one arcuate resiliently deformable clamping member having a radius of curvature less than that of an adjacent portion of said insulator, whereby opposite ends thereof are adapted to bear against the insulator portion, and adjustable means, including an externally adjustable screw element, associated with said clamping member for applying an inwardly directed radial deforming force against said clamping member, whereby said insulator is held in place by the spring force exerted by said ends resulting from the deformation of said clamping member.

15 4. In a support for insulators and the like, in combination, at least one arcuate resiliently deformable clamping member having a radius of curvature less than that of an adjacent portion of said insulator, whereby opposite ends thereof are adapted to bear against the insulator portion, and means associated with said clamping member for applying an inwardly directed radial deforming force against the center of said clamping member, whereby said insulator is held in place by the spring force exerted by said ends resulting from the deformation of said clamping member.

20 5. In a support for insulators and the like, in combination, at least one arcuate resiliently deformable clamping member having a radius of curvature less than that of an adjacent portion of said insulator, whereby opposite ends thereof are adapted to bear against the insulator portion, a fixed lug element adjacent the center of said clamping member on its outer side, said lug element having a tapped hole therethrough terminating at the center of said clamping member, and an adjustable screw 35 element associated with said lug element and bearing against the center of said clamping member for applying an inwardly directed radial deforming force against said clamping member, whereby said insulator is held in place by the spring force exerted by said ends resulting from the deformation of said clamping member.

40 6. In a support for insulators and the like, in combination, at least one arcuate resiliently deformable clamping member having a radius of curvature less than that of an adjacent portion of said insulator, whereby opposite ends thereof are adapted to bear against the insulator portion, said clamping member having a V-shaped cross section conforming to a similarly shaped cross section of the adjacent portion of the insulator, and means associated with said clamping member for

45 applying an inwardly directed radial deforming force against said clamping member, whereby said insulator is held in place by the spring force exerted by said ends resulting from the deformation of said clamping member.
